UNITED STATES PATENT OFFICE.

ZACHARY T. SCOTT, OF AUSTIN, TEXAS.

STEAM-CONDENSER.

1,156,501.

Specification of Letters Patent.

Patented Oct. 12, 1915.

Application filed February 17, 1915. Serial No. 8,838.

To all whom it may concern:

Be it known that I, ZACHARY T. SCOTT, a citizen of the United States, residing at Austin, in the county of Travis and State of Texas, have invented a new and useful 5 Steam-Condenser, of which the following is a specification.

The device forming the subject matter of 10 this application is a condenser, adapted to supply sterile water in hospitals and elsewhere, where a product of this sort is demanded.

The invention aims to provide a novel 15 means whereby at the will of an operator, steam may be mingled with the water of condensation when the same is discharged.

Another object of the invention is to provide a novel means whereby the outlet pipe which carries away the water of condensation 20 may be blown out by steam and be sterilized without causing such steam first to pass through the condenser.

It is within the scope of the disclosure to 25 improve generally and to enhance the utility of devices of that type to which the present invention appertains.

With the above and other objects in view 30 which will appear as the description proceeds, the invention resides in the combination and arrangement of parts and in the details of construction hereinafter described and claimed, it being understood that changes in the precise embodiment of the invention herein disclosed can be made within 35 the scope of what is claimed, without departing from the spirit of the invention.

In the drawings, the invention is shown 40 in a single vertical sectional figure, wherein sundry parts appear in elevation.

In carrying out the present invention 45 there is provided a condenser denoted generally by the numeral 1 and preferably in the form of a closed tank. The condenser 1 is surrounded by a jacket 2 which is closed.

The jacket 2 is held spaced from the 50 condenser 1 by means of brackets 3 and by means of a nozzle 4 constituting a part of a steam pipe 5, the nozzle 4 entering the top of the condenser 1 and passing through 55 packings 6 carried by the top of the jacket and the top of the condenser. The steam pipe 5 is provided with a valve 11 and communicates with the nozzle 4. Water is admitted into the space 7 between the condenser 1 and the jacket 2 through a pipe 8 having a valve 9. As the cooling water in

the space 7 rises in temperature, the water may be conducted away through a pipe 18 having a valve 19.

Branched off from the steam pipe 5 is an auxiliary steam pipe 10 communicating with one end of a casing 23 having an outlet 14. Communicating with the other end of the casing 23 and communicating with the interior of the condenser 1 is a pipe 15. Located in the casing 23 upon opposite sides of the outlet 14 are valves 16 and 17.

The invention may comprise a water gage 20, communicating with pipes 21 passing through packings 22 in the side wall 70 of the condenser 1 and in the side wall of the jacket 2, the pipes 21 communicating with the interior of the condenser 1.

Let it be supposed that the valves 16 and 17 are closed and that the valves 9, 19 and 11 are open. Then, the cooling water enters the space 7 between the condenser 1 and the jacket 2 through the pipe 8 and flows away by way of the pipe 18, the water rising as it becomes heated. Steam enters the condenser 1 by way of the pipe 5—4 and is condensed to form sterile water, within the condenser 1, as clearly shown in the drawing. The sterile water of condensation may then be withdrawn through the pipe 15—14 85 by opening the valve 17. When it is desired that the sterile water passing through the outlet 14 shall be heated somewhat, then the valve 16 is opened to a slight extent, whereupon steam from the pipe 5 will be delivered 90 into one end of the casing 23 through the pipe 10.

In order to sterilize the apparatus before the operation of condensing begins, the valves 11, 16 and 17 are opened. Then 95 steam passes by way of the pipe 5 and nozzle 4 into the condenser 1 and from the condenser through the pipe 15 into the casing 23 and out of the outlet 14. At the same time, steam passes from the pipe 5 by way of the pipe 10 into the casing 23 and out of the outlet 14. Not infrequently, a hose (not shown) is assembled with the outlet 14 and the outlet will be of much greater length than shown in the drawing. It is under such conditions that the pipe 10 is of 100 peculiar utility, so far as is concerned the sterilization of the pipe 14, since live steam is delivered by the pipe 10 from the pipe 5 directly into the casing 23 and the outlet 14, thus obviating the cooling of the steam 105 due to the expansion of the steam in the

condenser 1, it being obvious that, in the absence of the pipe 10, the pipe 14 could be steamed out and sterilized only by way of the pipe 4—5 and the condenser 1. The pipe 5 10, therefore, acts as a by-pass with respect to the condenser 1, delivering live steam into the pipe 14, independently of the condenser.

Having thus described the invention, what is claimed is:—

- 10 1. In a device of the class described, a condenser; a steam pipe communicating with the condenser adjacent its top; an outlet for the water of condensation; and means for selectively delivering to the outlet, steam, and water of condensation from the condenser.
- 20 2. In a device of the class described, a condenser; a casing having an outlet; valves in the casing and located upon opposite sides of the outlet; a conduit leading from one end of the casing to the lower portion of the condenser; and a steam supply pipe comprising branches, one of which branches enters the condenser adjacent its top, the other of which branches communicates with the other end of the casing.
- 25 3. In a device of the class described, a condenser; a steam pipe communicating with the condenser adjacent its top; an out-

let for the water of condensation; and means for selectively delivering to the outlet, steam from the steam pipe, and water of condensation from the condenser.

4. In a device of the class described, a condenser; a jacket completely inclosing the condenser; a cold water supply pipe discharging into the jacket; a cold water outlet pipe leading from the jacket; valves in the cold water pipes; a steam pipe embodying a branch passing through the jacket and entering the condenser adjacent the top of the condenser; and a branch leading downwardly to a point adjacent the bottom of the jacket; a valve in the steam pipe and controlling both branches; a casing into one end of which the last specified branch opens; a pipe leading from the other end of the casing through the jacket and communicating with the condenser; an outlet for the casing; and valves in the casing upon opposite sides of the outlet.

In testimony that I claim the foregoing as my own, I have hereto affixed my signature in the presence of two witnesses.

ZACHARY T. SCOTT.
